SPARK PLUG

Otto C. Rohde, Toledo, Ohio, assignor to Champion Spark Plug Company, Toledo, Ohio, a corporation of Delaware

Application April 30, 1936, Serial No. 77,156

4 Claims. (Cl. 123—169)

This invention relates to a spark plug and particularly to a plug which may be made of relatively small diameter.

The object of the invention is to produce a plug of simple construction which will be economical and efficient even when the diameter is relatively small.

Details of the invention will appear as the description proceeds.

10 In the accompanying drawing forming a part of this specification Figure 1 is an elevation of one form of spark plug embodying the invention; Fig. 2 is a longitudinal section of the plug shown in Fig. 1 and Fig. 3 is a section similar to Fig. 2 but showing a slightly modified form.

The plug shown in the drawing comprises a shell 10 having a screw threaded end 11 adapted to be screwed into the usual opening in the cylinder of an internal combustion motor or the like. Attached to the lower end of the shell is 20 electrode 12 in sparking relation with an electrode 13 mounted on the inner end of a conducting rod 14, the outer end 15 of which may be connected with any suitable source of current.

25 Shell 10 is formed with an internal shoulder 16 upon which there is mounted an insulating ring 17 which may be constructed of mica washers or equivalent material. The inner end of rod 14 rests upon the ring 17. The rod 14 is coated with a firmly adhering non-conducting 30 coating 18, preferably of enamel of high electric resistance. Enamels of considerable resistance have been developed to insulate conductors, but most of these enamels are not suitable for as high tension as must be met in a spark plug.

35 The addition of calcium borate to enamels otherwise suitable for insulating use renders the enamel more resistant, but it will be understood that in its broader aspect this invention contemplates the use of a sufficiently resistant enamel, however formed, and in this connection the term enamel is employed to cover any insulating coating which is applied to the rod and intimately adherent thereto so as to form the equivalent of enamel in the construction shown.

40 Between the lower end of rod 14 and shell 10 there is compacted powder 19 which may be powdered soapstone or the like. Preferably this powder is of a character to be compacted sufficiently to form a rigid gas-tight body and means for holding rod 14 securely in position within shell 10. Means is provided at the upper end of the shell to protect body 19 from moisture or the like. In the form shown this protection takes 45 the form of an inturned flange 20.

In the form shown in Fig. 3 the parts are the same as described in connection with Fig. 2 and are numbered the same, with the additional feature that, in the form shown in Fig. 3, a groove is provided in rod 14 in register with flange 20, and this groove is filled with an annular body 21 of insulating material. This insulating material may be either a separate body as shown in Fig. 3 or where more convenient may be integral with the insulating coating 18. It is obvious that if the insulation is insufficient at any point, it will be where the flange 20 approaches closely to rod 14, and consequently extra insulation may be provided as shown in addition to coating 18, if desired, or the coating may be made thicker at this point where necessary; but my preferred form contemplates employing a coating 18 of sufficient resistance to render it unnecessary to provide additional insulation within flange 20.

20 The sizes and proportions of parts may, of course, be varied to suit requirements and changes may be made within the scope of the appended claims. The most important single feature of this invention is the provision of the electrode mounted in a conducting rod, the rod 25 being provided with an insulating coating formed thereon and intimately adherent thereto like enamel, the rod being secured in position within the spark plug shell by frictional engagement with compacted powder or the like. 30

What I claim is:

1. A spark plug comprising a shell, a central conducting rod, an insulating coating formed on the rod and intimately adherent thereto and compacted powder between the shell and rod 35 forming a gas-tight body and securing the rod in position within the shell.

2. A spark plug in accordance with claim 1 and having a shell provided with an internal shoulder, an insulating ring mounted upon the shell and the inner end of the rod resting upon said ring.

3. A spark plug in accordance with claim 1 and having the outer end of the body of compacted powder protected by an inturned flange 45 of the shell.

4. A spark plug in accordance with claim 1 and having the outer end of the body of compacted powder protected by an inturned flange 50 on the outer end of the shell and having the insulating material around the rod thickened in an annulus within said flange.

OTTO C. ROHDE.
